DESIGN FOR AN ENGINE STARTING UNIT

Ralph M. Heintz, Cleveland, Ohio, assignor to
Jack & Heintz, Inc., Cleveland, Ohio

Application May 14, 1941, Serial No. 100,934

Term of patent 14 years

To all whom it may concern:

Be it known that I, Ralph M. Heintz, a citizen of the United States, residing at Cleveland, in the county of Cuyahoga and State of Ohio, have invented a new, original, and ornamental Design for an Engine Starting Unit, of which the following is a specification, reference being had to the accompanying drawing, forming part thereof, wherein:

Fig. 1 is a side view of an engine starting unit showing my design.

Fig. 2 is a side view taken at right angles to Fig. 1.

Fig. 3 is an end view of the starting unit.

I claim:

The ornamental design for an engine starting unit, substantially as shown.

RALPH M. HEINTZ.
